COFFEE MAKER OR SIMILAR ARTICLE

Robert O. Ernest, Oak Park, Ill., assignor to Sunbeam
Corporation, Chicago, Ill., a corporation of Illinois

Filed May 6, 1963, Ser. No. 74,758

Term of patent 14 years

(Cl. D44—26)

FIG. 4

FIG. 1 is a front elevational view of a coffee maker or similar article embodying my design;

FIG. 2 is a left side elevational view thereof;

FIG. 3 is a top plan view thereof;

FIG. 4 is a bottom plan view thereof; and

FIG. 5 is a fragmentary sectional view taken along line 5-5 of FIG. 3.

The dominant features of the design reside in the particular configurations of the side handles, cover knob and base members, in combination with an urn of the form shown.

I claim:

The ornamental design for a coffee maker or similar article, as shown and described.
